UNITED STATES PATENT OFFICE.

JOHN DAVIDSON, OF PROVIDENCE, RHODE ISLAND.

SPRINKLER-HEAD SHUT-OFF.

1,379,617.

Specification of Letters Patent. Patented May 31, 1921.

Application filed December 18, 1919. Serial No. 345,884.

To all whom it may concern:

Be it known that I, JOHN DAVIDSON, a citizen of the United States, and resident of the city of Providence, in the county of Providence and State of Rhode Island, have invented certain new and useful Improvements in Sprinkler-Head Shut-Offs, of which the following is a specification.

This invention relates to sprinkler-head 10 shut-off devices; and has for its object to provide a simple and effective closure member carried by a sprinkler head and adapted to be moved to close the discharge opening through the head at any time after the main closure member has been dislodged therefrom.

With this and other objects in view, the invention consists of certain novel features of construction, as will be more fully described, and particularly pointed out in the appended claims.

In the accompanying drawing:

Figure 1— is a sectional side elevation of my improved device.

Fig. 2— is a plan view sectioned on line 2—2 of Fig. 1.

Fig. 3— is a perspective view showing a detail of one of the auxiliary closure members.

It is found in the use of sprinkler systems for fire protection that sometimes the sprinkler head is accidentally or prematurely opened, and then again the head is often affected by an unimportant local blaze which has generated just sufficient heat to fuse and set off a near-by head, the fire being subsequently quickly extinguished, in both of which cases it is found to be of great importance to be able to quickly and readily 40 shut off the supply of water from this head itself in order to prevent excessive and unnecessary water damage.

My attachment is fitted as a part of the sprinkler head and is in position and ready 45 for immediate use, to shut off the escaping water from any sprinkler head without having to wait (as is necessary at present) until the main shut off is closed and the section drained of water.

To obviate this in a simple and practical way I have provided a closure member which is connected to, carried on, or forms a part of the head itself and which is always in position for immediate use to shut 50 off the water at the head without having to

wait until the valve at the main is reached and the section drained of its water.

The following is a detailed description of one form of device by which I am enabled to accomplish the desired results:—

Referring to the drawing, 10 designates the body of a sprinkler head, which comprises the usual neck 11 and a frame or yoke member 12. In the body is mounted the usual diaphragm 13 which is provided with a raised portion 22 on its base about its discharge opening 14, which opening is normally closed by a glass stopper 15 held in position by a link 16 which is formed of several parts locked together by solder or 60 readily-fusible material 17.

Through the opposite walls of this body portion 10 I have provided longitudinal slots 18 and 19 at points just above the diaphragm, and have mounted a plate or strip 20 to extend through the slot 18 across the face of the diaphragm and have its end 21 extend into the slot 19. This end portion 21 is preferably slightly beveled as at 23 whereby when the plate is moved inwardly 75 to its closed position, it is simultaneously forced downwardly onto the raised seat of the diaphragm, to effectually close the discharge opening 14 therethrough.

In this plate 20 I have preferably formed 85 a hole or opening 24 through which the main closure member extends whereby the plate or auxiliary closure is securely locked in position in the body portion and therefore is in operative position; but when the main 90 closure is for any cause removed, this auxiliary valve or closure may be engaged and hit or rapped with a stick or bar by a person on the floor, to close the opening and shut off the water and so in many cases prevent much damage by an excessive flow.

The auxiliary valve, gate, or closure is designed to fit closely in its two slots so that it cannot move except when pushed by the operator. Then again when the diaphragm is released after the displacement of the main closure member it springs upwardly and engages this plate by spring pressure further serving to hold it either when in opened or closed position. The 100 spring action of the diaphragm also serves to assist in preventing a leakage through the discharge opening when the gate or valve is in closed position.

This device while being in position in the 110

head for immediate use in shutting off the water at the head, is so designed as to in no way interfere with the free and full operation of the head in the event of fire.

5 Then again by connecting the shut off or closure member to the head it is always in position when wanted, which would not be the case if the closure were formed separate and disconnected from the head and kept at 10 some distant point.

The device is extremely simple and practical in its operation.

The foregoing description is directed solely toward the construction illustrated, 15 but I desire it to be understood that I reserve the privilege of resorting to all the mechanical changes to which the device is susceptible, the invention being defined and limited only by the terms of the appended 20 claims.

I claim:

1. A sprinkler-head comprising a body portion having a main closure member, and an auxiliary closure member, the latter being locked in said body by the positioning 25 of the former and having an operating portion extending laterally beyond said body.

2. A sprinkler-head comprising a body portion having a main closure member, an 30 auxiliary closure member provided with an opening said main closure when in operating position entering said opening to lock said auxiliary closure in inoperative position and said latter closure being released 35 by the removal of said main closure.

3. A sprinkler-head comprising an body portion having a main closure member seated therein, an auxiliary closure member having an opening therein through which 40 said main closure extends to engage its seat whereby said auxiliary closure is locked in inoperative position.

4. A sprinkler head having a body portion, a resilient diaphragm in said body having a discharge opening therethrough, a main closure member positioned to normally close said discharge opening, and a second closure member mounted to slide in said head in a plane different from that of said

diaphragm without affecting the operating 50 resiliency of said diaphragm and having a portion extending laterally beyond the body portion of the head to be readily engaged and moved to close said opening.

5. A sprinkler head having a body portion, a diaphragm in said head having a discharge opening therethrough, a main closure member positioned to normally close said discharge opening, a second closure member mounted in said head in position to be 60 readily moved to close said opening, and means whereby said latter closure is caused to press tightly against said diaphragm when moved to closed position.

6. A sprinkler head comprising a body 65 portion having a contracted discharge opening therethrough, a member for normally closing said opening, a closure plate slidably mounted in said head and adapted to be moved to closed position after said member 70 has been removed, and a beveled portion on said plate for causing it to press against its seat over the opening upon being moved to closed position.

7. A sprinkler head comprising an upper 75 and lower member, a separate intermediate body portion connected to said members, said body carrying a diaphragm having a central opening and being slotted through its side wall, a main closure for said opening 80 and an auxiliary closure slidably mounted in said slots and having an operating portion normally extending laterally a substantial distance beyond said body to be operated to close said opening when the main 85 closure has been removed.

8. A sprinkler-head comprising a body portion having a contracted discharge opening through it, a main closure member therefor, said body being provided with a transverse slot through it and a plate slidably mounted in said slot provided with an opening through which said main closure extends to its seat, said plate being adapted to be moved only after said closure has been 90 removed therefrom.

In testimony whereof I affix my signature,
JOHN DAVIDSON.
